UNITED STATES PATENT OFFICE.

ALBERT F. JONES, OF SALEM, MASSACHUSETTS.

SAW-BLADE.

No. 833,528.

Specification of Letters Patent.

Patented Oct. 18, 1906.

Application filed July 17, 1905. Serial No. 269,966.

To all whom it may concern:

Be it known that I, ALBERT F. JONES, of Salem, county of Essex, State of Massachusetts, have invented an Improvement in Saw-Blades, of which the following description, in connection with the accompanying drawings, is a specification, like characters on the drawings representing like parts.

This invention relates to saw-blades for sawing stone, and has for its object to provide a blade which may be made of soft metal, and consequently flexible, with teeth having straight stone-engaging faces or ends, and hard-metal wearing portions at both ends of said stone-engaging faces, which terminate flush with the ends of the teeth, the employment of said wearing portions resulting in reducing the wear on the teeth to the minimum and enabling the production of a flexible blade with very durable teeth.

Figure 1 shows in side elevation a portion of a saw-blade embodying this invention. Fig. 2 is a vertical section of the same, taken on the dotted line 2 2. Fig. 3 is a vertical section of the same, taken on the dotted line 3 3. Fig. 4 is an edge view of one of the hard-metal plates to be referred to.

a represents the body of the blade, which consists of a thin flat plate or bar of soft iron or equivalent material of any suitable dimensions and having a straight lower edge. The lower edge of the bar a is cut transversely at regular intervals to form semicircular or other shaped recesses a', and thereby provide the bar with a row of projecting teeth, the ends of which are straight and serve as stone-engaging faces. The bar thus made of soft iron or equivalent material for flexibility will wear away rapidly, and to obviate this hard-metal plates b are secured to the bar at the recessed portions thereof, which are constructed and arranged, as will be described, to provide wearing portions at both ends of the stone-engaging faces of the teeth. The plates b are made rectangular in shape and considerably thicker than the bar, and the edges of the plates, at the tops and both ends, are grooved, as at b². The width of the marginal grooves b² in the plates corresponds to the thickness of the bar a, so as to receive said bar, and the bottoms of said grooves correspond to the shape of the recesses in the bar, so that the plates may be placed upon or slid onto the bar at the recessed portions

thereof and abutted firmly against its lower edge, and when thus placed in position on the bar the lower edges of the plates will occupy positions flush with the stone-engaging faces of the teeth. The lower edges of the plates b are cut transversely to provide semicircular or other shaped recesses b', which form spaces between the teeth on the bar. The plates are secured to the bar by rivets c or other suitable fastenings. The hard-metal plates b thus inclose or cover the edges of the teeth on the bar, and as the lower ends of said plates terminate flush with the ends of the teeth hard wearing portions are provided at both ends of the stone-engaging faces of the teeth, which will be continued as the teeth thus protected slowly wear away. The wear on the teeth is thus reduced to the minimum.

In practice the water and sand used in sawing stone pass freely along the sides of the bar a, and as the bar is moved to and fro the same will repeatedly accumulate in and be removed from the interdental spaces b'.

Having thus described my invention, what I claim as new, and desire to secure by Letters Patent, is—

1. A saw-blade for sawing stone consisting of a bar recessed along its lower edge to provide teeth, plates secured to said bar, at the recessed portions thereof, the lower edges of which are terminated flush with the ends of the teeth on the bar to provide wearing portions at both ends of the stone-engaging faces of the teeth, and are formed with transverse recesses at points intermediate their length to provide interdental spaces, substantially as described.

2. A saw-blade for sawing stone consisting of a bar recessed along its lower edge to form teeth, plates secured to said bar, at the recessed portions thereof, which are made thicker than the bar, and have their lower edges terminated flush with the ends of the teeth on the bar, to provide wearing portions at both ends of the stone-engaging faces of the teeth, formed with transverse recesses at points intermediate their length to provide interdental spaces, and have their tops and both ends grooved to receive the bar, substantially as described.

3. A saw-blade for sawing stone, consisting of a soft-metal bar provided along its edge with projecting teeth having straight stone-

engaging faces or ends, and hard-metal plates inclosing the edges of said teeth, at both ends of their stone-engaging faces, which terminate flush with said stone-engaging faces, 5 and serve as wearing portions for the teeth, said plates having interdental recesses, substantially as described.

In testimony whereof I have signed my name to this specification in the presence of two subscribing witnesses.

ALBERT F. JONES.
